LOUIS STEINBERGER, OF BROOKLYN, NEW YORK.

INSULATOR.

1,166,392.

Specification of Letters Patent.

Patented Dec. 28, 1915.

Application filed February 10, 1912. Serial No. 676,879.

To all whom it may concern:

Be it known that I, LOUIS STEINBERGER, residing at Brooklyn, in the county of Kings and State of New York, have invented certain new and useful Improvements in Insulators, of which the following is a specification.

This invention relates to improvements in insulators, particularly such as are used 10 in connection with high potential transmission lines and which are to be rigidly secured to a suitable support or supports.

Among the objects of the invention may be stated: I. To provide an insulator for the 15 purpose referred to, to which I give a degree of strength commensurate with the use of metal, but without proportionate danger of arcing, and in which mechanical strains are well distributed. II. To provide an insulator 20 attaining the object above stated partly through the securing means employed and their relation to the insulator body. III. To provide in the insulator strengthened portions for receiving cables 25 or other members which may pull upon the insulator. IV. To provide an insulator of such construction that it may be rigidly supported at either one end or both ends, as desired. V. To provide an insulator construction 30 with a plurality of separate members for connecting it to a support or supports, said members extending entirely through the insulator body. VI. To provide an insulator 35 with a removable member extending entirely through the insulator, said member being provided at each end with means for securing it to a support.

Other objects and aims of the invention, more or less broad than those set out above, 40 together with the advantages inherent, will be in part obvious and in part specifically pointed out in the course of the following description of the elements, combinations, arrangements of parts, and applications of 45 principles constituting the invention; and the scope of protection contemplated will appear from the claims.

In the accompanying drawings, which are to be taken as a part of this specification, 50 and which show a merely illustrative form of the invention: Figure 1 is a central vertical section, with certain parts in elevation, showing an embodiment of my invention as in its supported position; Fig. 2 is a bottom 55 plan view of the insulator of Fig. 1, detached from its supports; Fig. 3 is a detail

of one of the strengthening members that take the strain of the cables; Fig. 4 is a central vertical section of the subject-matter of Fig. 3; and Fig. 5 is a view, partly in elevation and partly in section showing how the attaching parts of the insulator may be secured to a support at one end only.

Referring to the numerals on the drawings, I have shown at 6 an insulator body, 65 which may be of general cylindrical form. The insulator body 6 may be provided with a plurality of sheds 7, 8 and 9, of different sizes, the largest being at the top and the smallest at the bottom. Integral with the 70 shed 9 and with the insulator body 6 is a skirt 10 which extends downwardly from the insulator body. The opposite end of the insulator body may well be plane, as shown in Figs. 1 and 5.

Encircling the insulator body transversely are strengthening members 11, which in the illustrated embodiment take the form of rings having some such cross-section as shown, for instance, channeled rings, with 80 the bulge inward, and having lateral flanges whereby the effect of the cable strains is distributed. Preferably, these members are continuous rings, though obviously they may be non-continuous or in section, and 85 they may be molded in the body of the insulator, or otherwise secured thereto, as desired. These strengthening members 11 are located between the sheds 7 and 8 and 8 and 9, respectively, and serve to define and reinforce 90 the portions of the insulator body which take the strain of cables 12 or the like, said cables straining in opposite directions.

As a means for securing the insulator 95 body rigidly to a support, I provide a pair of members that extend entirely through the insulator body, transversely of the line of strain of the cables, said pair of members being accommodated in appropriate spaced 100 apertures, that extend therethrough from the plane top of the insulator body to the opposite end thereof that is surrounded by the skirt 10. If desired, these attaching members may take the form of bolts 15, 105 headed at one end and threaded at the other, which bolts, when the insulator body has been brought to position between spaced supporting arms 16, may be passed through the apertures in the insulator body. In 110 some cases I prefer to define and reinforce the apertures through the insulator body by

means of tubular members 17 that project beyond the opposite ends of the body, these tubular members being rigidly molded in the material of the body. In such case I 5 may thread the tubes exteriorly at their ends; when the headed bolts 15 are dropped into place they may be rigidly held relatively to the arms 16 by means of nuts 18, washers being interposed between said nuts 10 and the lower arm 16; at the same time, the insulator body might be held rigidly with relation to the bolts 15 by means of nuts 19 on the threaded end or ends of the tubes 17 engaging the insulator body at one or both 15 ends. Again, I may dispense entirely with the bolts 15, and provide merely the tubular members 17, having exteriorly threaded ends extending well beyond the opposite ends of the insulator body, molded or mov- 20 able in the apertures of the body, with which ends are engaged nuts 18. In case I wish to secure the insulator body to each of a pair of spaced arms 16, as in Fig. 1, the nuts 25 may engage the top of the upper arm and the lower face of the lower arm. If the space between the arms is greater than the length of the insulator body, I may cause the plane top of the insulator to abut the under face of the upper arm, and cause it to hold 30 that position by means of nuts 19 engaging the lower end of the insulator within the skirt 10. And indeed similar nuts 19 might engage the plane end of the insulator body also, so as to hold the insulator spaced from 35 both arms 16.

The members 17, whether employed as direct attaching members, or as auxiliary attaching means with the bolts 15, being tubular, are of a more or less elastic nature 40 transversely of their length so that any expansion or contraction of the fickle material within which they are embedded may be accommodated without danger of fracture to the material, as might follow were 45 the members 17 solid.

In Fig. 5 I have shown how the insulator may be secured to a single arm 16, from which it depends. Here I show tubes 17 extending through the insulator body, with 50 their opposite ends exteriorly threaded, nuts 19 on the upper ends of the tubes engaging the arm 16, against the lower face of which abuts the plane top of the insulator body, and other nuts 19 on the lower ends of the 55 tubes engaging the lower end of the insulator within skirt 10. Obviously, with respect to Fig. 5, I may use a combination of tubes and bolts, as in Fig. 1. And in every case, the securing members whether tubes 60 or bolts, may be molded or slideable in their apertures. It is of course advantageous to have the apertures that extend through the insulator, in the line of a diameter of the insulator, which line is also the line of strain 65 of the cables.

The construction described has the advantage that it is most readily put into and removed from position, and affords a maximum of strength and rigidity in resisting strains, and that it is also readily adaptable 70 to the varying requirements arising in practice.

It will be understood that I do not limit myself to the particular form of insulator herein shown, nor to the exact form or ar- 75 rangement or number of the securing members, nor to the use of any particular material. I prefer, however, for the insulator body, to employ the insulating material known in the art as "Electrose." 80

As many changes could be made in the above construction without departing from the scope thereof, as defined in the following claims, it is intended that all matter contained in the above description, or shown in 85 the accompanying drawings, shall be interpreted as illustrative only and not in a limiting sense.

Having thus described my invention what I claim as new and desire to secure by Let- 90 ters Patent, is:

1. An insulator comprising a body of insulating material having a plurality of apertures extending therethrough, tubular members extending through said apertures, and attaching members extending through said tubular members and provided at their ends with means for securing them to a support. 95

2. An insulator comprising a body portion of insulating material having an aperture 100 extending therethrough; and a plurality of separately formed attaching members ex- 105 tending through said aperture and project- ing therebeyond whereby the insulator may be connected to a support, one of said mem- bers being tubular and another of said mem- bers extending through the hollow of the first.

3. An insulator comprising a substantially cylindrical body portion of insulating mate- 110 rial; having an aperture extending there- through; a tubular reinforcing member within said aperture, retaining means for the insulator extending through the hollow of said tubular reinforcing member; and an 115 annular reinforcing member fitted upon the outer surface of said body adapted to accommodate cables or the like.

4. An insulator comprising a body of in- 120 sulating material; a tubular metallic rein- forcing member embedded therein project- 125 ing beyond relatively opposite surfaces thereof and being adapted to receive retaining means for holding such insulator in fixed relation to a support, and the project- ing portions of said reinforcing member having means for retaining said body in an adjusted position on said reinforcing mem- ber.

5. An insulator comprising a body of in- 130

5 sulating material having an aperture extending therethrough, an attaching member extending through said aperture having its opposite ends threaded and projecting from the opposite ends of the body, said attaching member being tubular to form a reinforcing means for the body, means engaging the threads of said attaching member to retain the body thereon, and auxiliary attaching 10 means extending through said tubular attaching member.

6. An insulator comprising a body of insulating material having an aperture therethrough, a tubular member co-axial with 15 said aperture extending from the body at one end of the aperture, a rod extending through said aperture and through the tubular member being longitudinally movable therein, adjustable means engaging between 20 one end portion of said rod and said tubular member for connecting the insulator to a support, and means at the opposite end of the tubular member for engaging a second support, the adjustable means at the first 25 mentioned end of said rod being adapted to move the rod relatively longitudinally to cause the support engaging means at the second end of the rod to clamp the insulating body against the second support.

7. An insulator comprising a body portion 30 of insulating material, having an aperture extending therethrough, and a plurality of separately formed attaching members extending through said aperture, the opposite 35 ends of one of said attaching members being extended beyond said aperture to engage a support, the other of said attaching members having heads thereon beyond the opposite ends of the first attaching member, 40 said heads comprising means for engaging said support to retain the first attaching member in attached relation to the support.

8. An insulator comprising a body portion of insulating material having an aperture extending therethrough, and a plurality 45 of separately formed attaching members extending through said aperture, one end of one of said attaching members being extended beyond said aperture to engage a support, a means carried by the other attaching member for engaging the support to retain the first attaching member in attached relation to the support.

9. The combination with an apertured support, of an insulator to be supported 55 therefrom, said insulator having an aperture formed therethrough, an attaching member extending through the aperture in said insulator and engaging in the aperture in said support, and means extending 60 through the aperture in the insulator and engaging said support to retain said attaching member in attached relation to the support.

10. The combination with an apertured 65 support, of an insulator to be supported therefrom, having an aperture therethrough, an attaching member extending through the aperture in said insulator and projecting therefrom into the aperture in said support, 70 said attaching member being tubular, and means extending through the opening in said tubular attaching member and extending beyond the end of said tubular attaching member into engagement with said support to retain said attaching member against 75 detachment from the aperture in said support.

In testimony whereof I affix my signature in the presence of two witnesses.

LOUIS STEINBERGER.
